UNITED STATES PATENT OFFICE

167,258

JET-PROPELLED AIRPLANE

Bert T. Doi, Pasadena, Calif.

Application June 4, 1951, Serial No. 15,418

Term of patent 3½ years

(Cl. D71—1)

To all whom it may concern:

Be it known that I, Bert T. Doi, a citizen of the United States, residing at Pasadena, in the county of Los Angeles and State of California, have invented a new, original, and ornamental Design for a Jet-Propelled Airplane, of which the following is a specification, reference being had to the accompanying drawing, forming part thereof.

Figure 1 is a side elevational view of a jet-propelled airplane showing my new design;

Figure 2 is a front elevational view thereof; and

Figure 3 is a top plan view of the same.

The essential features of the design reside in the features shown by means of full lines.

I claim:

The ornamental design for a jet-propelled airplane, as shown and described.

BERT T. DOI.
